ROTATABLE VALVE AND SWITCH SUPPORT
FOR ENDOSCOPIC INSTRUMENTS

Harry S. Rubens, Manhasset, and Ignaz Suwa,
Jackson Heights, N. Y., assignors to National
Electric Instrument Co., Inc., Elmhurst, N. Y.,
a corporation of New York

Application August 7, 1948, Serial No. 43,097

5 Claims. (Cl. 128—7)

1

The present invention relates generally to improvements in an endoscopic instrument and more particularly to improvements in a cystoscope or the like diagnostic and treating instrument.

The cystoscope comprises, for example, an outer sheath or tube adapted for insertion into a body cavity through an opening, natural or otherwise, whereby said body cavity is to be illuminated, examined and treated through a fenestral opening provided in said tube. The fenestral opening, prior to the insertion of the cystoscope into the body cavity or withdrawal therefrom, is substantially closed by means of an obturator so that the edges of the fenestrum do not cause injury during passage into or out of the body cavity.

After the tube has been inserted, the obturator is withdrawn and replaced by a telescopic optical system through which the body cavity is observed—under illumination produced by an incandescent lamp provided inside the tip of the outer cystoscope tube and which is adapted to illuminate through the fenestrum—while being treated, etc. Clear vision of the body cavity, e. g. the bladder, is generally accomplished by dilating such cavity under fluid pressure maintained and controlled by a valve arrangement at the rear of the cystoscope outer tube. Such valve arrangement usually has the valve mechanism and conduits secured in a fixed position at the rear of the cystoscope outer tube so that when the tube is rotated during body cavity examinations, etc., the entire valve assembly and attached tubing, e. g. rubber tubing utilized for flushing and for providing fluid for the distension of the body cavity, also rotate with the tube and inhibit the ease of manipulating the cystoscope, said ease of manipulation being very desirable in that the greater the ease of manipulation, the less the discomfort to the patient. Furthermore, cystoscopes as known are provided with either an electrical terminal fixed to the outer tube and having the same disadvantage as the fixed valve assembly, or they are provided with a rotary contact having distinct advantages over the fixed terminal, which, however, does not provide the desired ease of manipulation due to a substantially large frictional contact area.

It is one object of this invention to provide a cystoscope or the like instrument with a combination comprising a valve assembly and an electrical contact with a cooperating switch system adapted for easy manipulation of the instrument. It is another object of this invention to provide a cystoscope with an improved electrical contact

2

and cooperating switch system. Other objects and advantages of the invention will become apparent from the description hereinafter following the accompanying drawings forming part hereof, in which:

Figure 1 illustrates an elevational view of the cystoscope structure of the invention showing the combined electrical contact and cooperating switch system and valve assembly,

10 Figure 2 illustrates a right angle view of Figure 1 with the lever arms in angular displacement, and

Figure 3 illustrates an enlarged longitudinal-sectional view, partly in elevation, of Figure 1.

15 According to the present invention, we provide an improved cystoscope structure comprising a combination of a valve assembly and a rotatable electrical contact with a cooperating switch system, said valve assembly and switch system being mounted on a single freely rotatable member thereby providing a cystoscope which may be manipulated with great ease particularly in view of the fact that the cystoscope outer sheath or tube may be rotated independently of encumbrances which interfere with the manipulation of the cystoscope in the examination, etc., of body cavities. The freely rotatable member more particularly described hereinafter allows such cystoscope attachments, e. g. tubing and wire leads,

20 which otherwise would interfere with examinations, to assume a constant position and maintain such position regardless of the rotation of the cystoscope tube while in position for examination.

25 In Figure 1, we have shown the cystoscope structure of the invention comprising a freely rotatable member 1 having mounted thereon a valve assembly 2 and an electrical switch system 3 so positioned that the contact pin 4 may cooperate

40 and maintain contact with the contact ring 5 during rotation of the tube 6 by means of a handle 7. Since the member 1 is freely rotatable, it is apparent that the elements mounted thereon and any attachments to such elements will assume a constant position or simultaneous movement regardless of the rotation of the tube 6.

45 In Figure 2, taken at right angles to Figure 1, we have more particularly shown the nature of the valve assembly, in this case a plurality of valves is indicated, comprising a valve lever 8 and a conduit or nipple 9 to which tubing may be attached through which fluid under pressure may pass for the irrigation and distension of the body cavity. Each valve cooperates with an orifice or opening in the cystoscope tube or sheath. The

lever arms 10 and 11 relate to the locking device provided for the cystoscope of the invention.

Figure 3 illustrates a longitudinal-sectional view of the structure of our invention and particularly shows the various embodiments in detail. The rotatable member 1 rotates freely about the tube support or tube body 12 between the complementary beveled abutment 13, which is provided with a circular groove 14 for sealing lubricant, and a complementary beveled sealing nut 15, which is similarly provided with a circular groove 16. The sealing nut 15 is properly adjusted with respect to the rotatable member 1 by a screw action on the threaded body 12 and retained in proper aspect for free movement of rotatable member 1 by means of the set screws 17 and 18. Having positioned and secured the rotatable member 1, a contact ring 5 is positioned coaxial with the tube 6 between two insulating rings 19 and 20 and secured by means of the flange 21 on the threaded tube body 12. An insulated conductor (not shown) leading to the cystoscope lamp is caused to contact the contact ring prior to the securing of said contact ring on the body 12 by means of the flange 21.

For purposes of irrigation or distension of the body cavity, openings or orifices 22 and 23 are formed through the tube body 12 and separated from each other by the collar 24 so that each orifice cooperates with one of the valves identified by the valve assembly 2 of Figure 2 and one of the annular grooves provided between the rotatable member 1 and the tube body 12 of Figure 3. However, the collar 24 may be eliminated and both valves may be fed through a single common 35 orifice.

The electrical switch system 3 comprises a housing 25 which is removable with respect to the rotatable member 1. Upon insertion of the housing 25 into the short tubular structure or barrel portion 26 of the rotatable member 1, a circular groove with detent 27 is caused to engage a detent pin 28 which holds the housing in proper position for the contact pin 4 to contact the contact ring 5, said detent pin 28 being provided with a spring tension by means of the detent spring 29 and being retained within certain movable limits by the action of the retainer pin 30 in the slot 31. The contact pin 4 is insulated from the housing 25 by means of the slideable contact insulator 32 which is diametrically slotted at its extremity to allow the contact pin 4 to contact the contact ring 5 as illustrated. From the illustration, it is apparent that the contact pin 4 is recessed in said diametrical slot so that the pin can contact only the rim or edge of the contact ring. However, when the housing 25 is rotated, for example, 90°, the contact insulator 32 rotates similarly causing the raised portions of the insulator to contact the contact ring 5 and disengage the contact pin 4 from the edge of the contact ring 5 and in this manner causes an opening of the electrical circuit or places the switch in the "off" position. The proper slideable motion for the contact insulator 32 is provided by a spring (not shown) inside the guide assembly 33 through which is an insulated lead from the contact pin to the electrical cord which terminates at the source of current supply, said guide assembly is insulated from the housing 25 by means of the insulator ring 34. The complete circuit is established with the provision of a ground illustrated at 35 inside the electrical switch housing 25. To provide the cystoscope lamp with current supply, it is only necessary to

rotate the housing 25 approximately 90° so that the contact pin 4 again contacts the contact ring 5 under the spring tension of the spring inside the guide assembly 33. This spring tension, although sufficient to maintain contact between the contact pin and the contact ring, is nevertheless, not sufficient to cause the detent pin 28 to disengage from the detent 27 so that the housing 25 still remains securely in position regardless of the thrust of the switch spring inside the guide assembly 33.

The slotted arrangement of the contact insulator is particularly advantageous in that should the switch system be temporarily removed from the barrel portion 26 of the rotatable member 1, and set aside, there would be no great danger of a short circuit resulting from contact of the contact pin with a metallic instrument, etc., since the contact pin is almost entirely protected by the raised portions at the contact insulator extremity.

Of particular importance is the fact that in the combination of the contact pin and contact ring, according to the invention, only a minimum contact surface is provided which does not greatly interfere with the freely rotatable member 1, since there is no great frictional drawback.

It is, therefore, apparent that we have provided an improved cystoscope structure directed primarily for the efficient and easy manipulation of a cystoscope by the novel combination herein described.

However, the invention is not limited to the specific illustrations and description herein set forth as relating to the cystoscope, but may be construed to include, generally, improvements for endoscopic instruments falling within the true scope of the invention.

What we claim is:

1. In an endoscopic instrument, the combination comprising an endoscopic tube and support therefor, an electrical contact ring positioned on said support coaxial with said endoscopic tube and insulated therefrom, a rotatable member 45 mounted on and rotatable about said support, said rotatable member having mounted thereon an electrical switch system and a valve assembly cooperative with an orifice formed through the wall of said endoscopic tube, said electrical switch system comprising a rotatable housing detachable from said rotatable member, said housing containing an axially moveable contact insulator having a diametrically slotted end and recessed therein a contact pin, said contact pin being cooperative with said contact ring to provide an electrical switch operable upon rotation of said rotatable housing.

2. In an endoscopic instrument according to claim 1, a recessed contact pin engageable with only an edge of said contact ring, said housing and contact insulator being angularly disposed toward said edge.

3. In an endoscopic instrument according to claim 1, said electrical switch system including wiring therefor and said valve assembly including tubing therefor being supported by a single rotatable member for simultaneous movement in relation to said endoscopic tube.

4. In an endoscopic instrument, the combination comprising an endoscopic tube and support therefor, an electrical contact ring positioned on said support coaxial with said endoscopic tube and insulated therefrom, a rotatable member mounted on said support between beveled supporting means complementary with said rotata-

ble member, said rotatable member having mounted thereon an electrical switch system and a valve assembly, said valve assembly being co-operative with an orifice formed through the wall of said endoscopic tube, said electrical switch system comprising a rotatable housing detachable from said rotatable member and angularly disposed toward an edge of said contact ring, said housing containing an axially moveable contact insulator having a diametrically slotted end and recessed therein a contact pin, said recessed contact pin being engageable with only an edge of said contact ring to provide an electrical switch operable upon rotation of said rotatable housing, said beveled supporting means and said edge of said contact ring providing a minimum friction surface, said rotatable member being freely rotatable.

5. In an endoscopic instrument according to claim 4, said rotatable member having a short tubular structure secured thereto, said detachable housing being insertable into said short tubular structure of said rotatable member, said

6
tubular structure being angularly disposed in the direction of said contact ring, said housing having an annular groove engageable with a spring activated means for maintaining said housing secured to said rotatable member during rotation of said housing.
